(57) CLAIM

The ornamental design for a motorized wheelbarrow, as shown and described.

DESCRIPTION

FIG. 1 is a left side perspective view of a motorized wheelbarrow showing my new design;

FIG. 2 is a right front perspective view thereof;

FIG. 3 is a rear perspective view thereof; and,

FIG. 4 is a front perspective view thereof.

The broken line showings of wheels, an electric motor, a battery pack and associated wiring are for illustrative purposes only and form no part of the invention.
